CIRCULAR KNITTING MACHINE

Alexander Kaufman, Long Island City, N. Y.

Application February 27, 1935, Serial No. 8,452

1 Claim. (Cl. 66-36)

This invention relates to new and useful improvements in a needle separating method for circular knitting machines.

The use of pattern wheels for knitting machines is generally known. These wheels function to separate the needles of the knitting machine to different elevations to control the knitting operation. This invention has particular reference to a novel association of a pattern wheel with the knitting machine to perform the functions stated, and distinguishes from the prior devices merely in structural features.

More particularly, the invention proposes the mounting of a pattern wheel on the usual cam which lifts the needles in such a manner that certain of the needles are lifted the full distance, and others of the needles are only partially lifted and thereafter are forced behind the cam.

More particularly, the invention makes use of needles having flexible butts engaging the cam and wherein the pattern wheel is capable of flexing the needles as desired out of contact with the cam so that they maintain intermediate positions.

Still further the invention contemplates the provision of cams to return all of the needles to their initial positions.

Another object of the invention is the construction of a device as mentioned which is simple and durable and which can be manufactured and sold at a reasonable cost.

For further comprehension of the invention, and of the objects and advantages thereof, reference will be had to the following description and accompanying drawing, and to the appended claim in which the various novel features of the invention are more particularly set forth.

In the accompanying drawing forming a material part of this disclosure:—

Fig. 1 is a schematic developed view of a portion of a circular knitting machine constructed according to this invention.

Fig. 2 is a fragmentary sectional view taken on the line 2-2 of Fig. 1.

Fig. 3 is a fragmentary plan view of the device, a portion thereof being shown in section.

The invention is used in conjunction with a circular knitting machine having a needle cylinder 10 associated with a plurality of knitting needles 11. These needles have offset resilient butts 12 normally engageable by a cam 13 to raise the needles to an elevation indicated by reference numeral 14. The needle cylinder 10 is shown formed with vertical slots (see Fig. 2) in which the needles 11 slidably engage. The

flexibility of the butts 12 consist in bent lower portions of the needles arranged in such a manner that the lower portions may be forced inwards, as indicated by the dot and dash lines in Fig. 2.

A pattern wheel 15 is rotatively mounted upon a stud 16 supported in a bracket 17 which is attached upon the cam 13. This pattern wheel is arranged intermediate of the extremities of the cam 13, as clearly shown in Fig. 1.

The pattern wheel is formed with peripheral cutouts 15^a for meshing with the butts 12 of the needles to cause the pattern wheel to turn and also to allow the butts to ride upon the cam 13. The pattern wheel 15 is also formed with peripheral notches 19 for engaging the butts 12 of needles 11 to flex the butts off of the cam 13 and simultaneously to cause the pattern wheel to turn. When the butts are flexed off the cam they will be forced into the grooves of the needle cylinder and become wedged between the back face of the cam and the groove so as to maintain their partially raised positions.

In Fig. 1 the butts 12 of a plurality of needles are shown progressively extended up along the cam 13. Above the pattern wheel 15, only certain of the butts are shown upon the cam, and others of the butts shown behind the cam. The butts shown on the cam are indicated by reference numerals 12^a and those behind the cam by numerals 12^b. The butts 12^a are raised the complete height to the altitude indicated by reference numeral 14. The needles, indicated by the butts having reference numerals 12^b are only raised partially by the cam 13 until that time when they are forced off the cam by the pattern wheel.

A cam 20 is mounted upon the cam 13 and serves to lower the needles, indicated by the butts 12^b when desired, back to their initial positions. A cam 21 serves to lower the needles having the butts 12^a back to their initial positions. The area indicated by reference numeral 22 is one in which all of the butts are again at the same elevation.

Particular attention is called to Fig. 3 wherein it should be noted that the butts 12 are riding upon the cam 13 and the cutouts or notches of the pattern wheel control whether these butts may continue upon the cam or be forced off of the cam and behind the cam. Numerals 12^a indicate the butts returning on the cam, and numerals 12^b, the butts which have been forced behind the cam.

The purpose of causing the needles to assume

different elevations are generally known in the knitting art. When the needles are at different elevations, various types of stitches will be produced, such as "tuck" stitches, "welt" stitches, 5 etc.

While I have illustrated and described the preferred embodiment of my invention, it is to be understood that I do not limit myself to the precise construction herein disclosed and the right 10 is reserved to all changes and modifications coming within the scope of the invention as defined in the appended claim.

Having thus described my invention, what I claim as new, and desire to secure by United 15 States Letters Patent is:—

In a circular knitting machine, a needle cylinder formed with vertical peripheral slots, knitting needles slideable in said slots and having offset resilient butts extending from said slots, a 20 cam associated with said butts to raise the

needles, a pattern wheel rotatably mounted on said cam between the extremities of the cam and having peripheral cut-outs for meshing with the butts of the needles to turn the pattern wheel, and also having peripheral notches of considerably less depth than the slots for engaging the butts of the wheel to flex the needles off the cam at only partially raised elevation and to turn the pattern wheel, a knitting cam to return all fully raised needles, and a cam to return 5 all partially raised needles to initial elevation, the butts which have been flexed off the cam resiliently engaging the back of the cam for maintaining their partially raised positions, said pattern wheel being arranged at an inclination corresponding with the inclination of the cam upon which it is mounted, and the pattern wheel 10 meshingly engaging the needle butts during the raising motion of the latter.

ALEXANDER KAUFMAN. 20
